(57) **CLAIM**

The ornamental design for a sifter pan, as shown and described.

DESCRIPTION

FIG. 1 is a top perspective view of a sifter pan showing my new design;

FIG. 2 is a bottom perspective view thereof;

FIG. 3 is a top view thereof;

FIG. 4 is a bottom view thereof;

FIG. 5 is a right side elevational view thereof, with the left side elevational view being identical thereto;

FIG. 6 is a front elevational view thereof, with the rear elevational view being identical thereto; and,

FIG. 7 is an exploded perspective view thereof as seen from the bottom of the pan.

The broken line showing of a screen in FIGS. 4 and 7 is for illustrative purposes only and forms no part of the claimed design.

1 Claim, 4 Drawing Sheets(56)
